PRESERVATION OF GLYCERIDE OILS

Kenneth C. D. Hickman and James G. Baxter,
Rochester, N. Y., assignors to Distillation Prod-
ucts Inc., Rochester, N. Y., a corporation of
Delaware

No Drawing. Application October 5, 1938.
Serial No. 233,496

3 Claims. (Cl. 260—398.5)

This application concerns the prevention of oxidation of natural glyceride oils. More particularly it relates to the preservation or prevention of oxidation of natural glyceride oils by chemical means other than the addition of true anti-oxidants thereto.

It is currently believed that fatty oils are oxidized in a series of stages which probably involve chain reactions. The oxidation results in the formation of aldehydes, ketones, free fatty oils and other substances which impair flavor and odor and impart other undesirable properties. The manner in which the oxidation takes place and methods for protecting against oxidation have been actively investigated, but the problem has not been previously solved. The protection of vitamin containing oils is of particular importance because these expensive substances are destroyed simultaneously with the oil.

This invention has for its object to provide an improved method for protecting glyceride oils, fractions thereof, and/or substances derived therefrom against oxidation. A further object is to provide an improved method for protecting vitamin containing oils, against oxidation. A further object is to provide a method whereby the peroxide content of natural glyceride oils and the like is prevented from exerting its harmful action. A still further object is to provide a method for protecting glyceride oils against oxidation, by means other than the addition of anti-oxidants to the oil itself. Other objects will become apparent as the description of the invention proceeds.

We have discovered that peroxides contained in natural glyceride oils can be directly removed from the oil substantially as fast as formed by disposing or storing it in contact with a layer of water which is immiscible with the oil and which contains a substance capable of reacting with and destroying the peroxide content of the oil. Peroxides in the oil pass or diffuse into contact with the immiscible layer where they are effectively captured and prevented from exerting harmful action. We have further discovered that as long as the peroxides are effectively removed from the oil the rest of the oxygen which remains dissolved in the oil will exhibit little or no harmful action. Since this procedure does not involve the direct addition of an anti-oxidant to the oil and dispersion of such materials throughout the oil, problems of removing such substances or subsequent purification of the oil are avoided.

Substances which react with peroxides are well

known and can be selected from any up-to-date text book on organic chemistry. Where the suitability of a particular material is in question its action can be determined by means of a simple experimental test. Examples of suitable materials are alkali bicarbonates and alkali sulfites such as sodium bicarbonate, sodium sulfite or calcium sulfite and mixtures thereof; neutral hydrosulfites such as potassium hydro-sulfite; alkali phosphites; hypophosphites; ferrous, cerous, manganous, titanous, stannous and chromous salts such as ferrous chloride and cerous sulfate; hydroquinone, and salts and other derivatives of hydrazine, hydroxylamine, aromatic phenols and amines.

In the case of the highly reactive reducing agents such as hydrazine, hydroxylamine, the phenols, hydroquinone and aromatic amines the immiscible layer or solution can contain rather minute quantities such as up to one tenth of one percent. They may be prevented from passing into the oil phase, if there is such a tendency, by the addition of alkali and/or alkaline sulfites. The other peroxide destroying substances listed above usually should be employed in somewhat higher proportions such as one to 20 percent based on the amount of immiscible solvent. Saturated solutions of these materials are quite successful. These proportions are not critical and can be varied substantially.

The invention may be employed to protect glyceride oils and fats or fractions thereof which are subject to destruction due to oxidative influences. Examples of such substances are cod liver, halibut liver, menhaden, tuna liver, etc. fish oils; soy bean, cottonseed, olive, linseed, etc. oils. Examples of fats which may be protected are butter, lard, and hydrogenated oils. Our invention is of particular advantage for protecting vitamin containing oils and fractions thereof, such as the fractions obtained by high vacuum distillation of such oils, which fractions contain a high concentration of valuable vitamins.

In the following example the oil to be protected was exposed much more drastically to air and/or peroxides than it would be under normal storage conditions where the protection afforded by the invention would be much greater.

50 Example

10 cc. of vitamin A concentrate prepared from pollack oil by distillation at a pressure of approximately .001 mm. in a high vacuum, short path still was added to a cylindrical glass vessel approximately 1 1/2" in diameter. To a similar

vessel containing 10 cc. of 10% aqueous sodium sulphite was added an equal portion of pollack concentrate. The containers were then loosely plugged with absorbent cotton and allowed to stand in diffused light at room temperature. At appropriate intervals vitamin A determinations recorded in the table below were made:

Composition	Assay 0 days	Assay 7 days	Assay 13 days	Assay 17 days
Pollack concentrate.....	41,000	39,700	12,700	3,760
Pollack concentrate with 10 percent aqueous sodium sulphite.....	41,000	39,800	29,800	8,540

It is apparent from the data that a substantial protection was afforded the vitamin content of the oil by the immiscible aqueous sodium sulphite layer upon which the vitamin containing oil was floated. Since the test conditions were much more drastic than normal storage conditions, the protection afforded by the invention would be much greater under ordinary conditions.

What we claim as new and desire to be secured by Letters Patent of the United States is:

1. The process of protecting a glyceride oil which contains vitamin A against oxidation without actual admixture of a protecting agent therewith whereby the vitamin A and the glyceride oil can be stored without substantial deterioration and can be separated with ease from the protect-

ing agent, which process comprises in combination floating a body of the glyceride oil of substantial bulk during the period of protection upon an aqueous body immiscible with the oil in which aqueous body is dissolved a substance capable of reacting with peroxides.

2. The process of protecting a glyceride oil against oxidation without actual admixture of a protecting agent therewith whereby the glyceride oil can be stored without substantial deterioration and can be separated with ease from the protecting agent, which process comprises in combination floating a body of the glyceride oil of substantial bulk during the period of protection upon an aqueous body immiscible with the oil in which aqueous body is dissolved a substance capable of reacting with peroxides.

3. The process of protecting a glyceride oil which contains vitamin A against oxidation without actual admixture of a protecting agent therewith whereby the vitamin A and the glyceride oil can be stored without substantial deterioration and can be separated with ease from the protecting agent, which process comprises in combination floating a body of the glyceride oil of substantial bulk during the period of protection upon an aqueous body immiscible with the oil in which aqueous body is dissolved sodium sulphite.
